DESK OR SIMILAR ARTICLE

Douglas C. Ball, Senneville, Quebec, Canada, assignor to
Massey-Ferguson Industries Limited, Toronto, Ontario,
Canada

Filed Aug. 30, 1973, Ser. No. 393,250

Term of patent 14 years

Int. Cl. D6—04

U.S. Cl. D6—162

Fig. 1

Fig. 2

Fig. 3

Fig. 4

Fig. 5

FIG. 1 is a front elevational view of a desk or similar article showing the end supports and a drawer unit;

FIG. 2 is a right side elevational view of a desk or similar article in FIG. 1 showing the table top and drawer projecting outwardly therefrom;

FIG. 3 is a rear elevational view of a desk or similar article in FIG. 1 showing the rear panel thereof;

FIG. 4 is a left side elevational view of a desk or similar article in FIG. 1 showing the table top and drawer projecting outwardly therefrom; and

FIG. 5 is a top view of a desk or similar article in FIG. 1 showing the end supports projecting beyond the rear panel.

I claim:

The ornamental design for a desk or similar article, substantially as shown.
